UNITED STATES PATENT OFFICE

2,300,603

COIN HANDLING MECHANISM

John C. Wahl, Chicago, Ill., assignor to Lion Manufacturing Corporation, Chicago, Ill., a corporation of Illinois

Application July 30, 1938, Serial No. 222,247

5 Claims. (Cl. 194—98)

The invention relates to a coin chute and coin handling or feed mechanism for use with coin feed mechanisms such as vendors, amusement apparatus, or the like.

It is desirable that such coin handling mechanism be certain in operation and free of mechanical difficulties caused when unscrupulous persons attempt to pass unauthentic coins or checks through the coin handling or feed mechanism. To that end the mechanism should include effective means to reject or by-pass magnetic slugs and undersized slugs or coins, as well as to prevent jamming in the event two coins are accidentally fed into the mechanism at the same time. Further, it is desirable to provide means to move a certain number of previously fed coins in a display position behind a window before discharging same into a cash box, such means additionally serving to prevent petty cheating because by making all coins handled visible there is a strong psychological deterrent to the use of unauthentic coins, even if some can be found that might be used in spite of the aforementioned safeguards.

With these problems presented, the main object of the invention is to provide an improved coin chute or coin handling mechanism for the purposes stated.

Another object is to provide a mechanism of the kind stated, which will include means to reject or by-pass most types of unauthentic coins without jamming the mechanism.

Another object is to provide means to prevent two coins from passing into the mechanism at the same time and insure that they will pass through successively.

Another object is to provide an improved Escalator means for displaying a number of previously used coins in a display position before they are moved to a cash box, or the like.

It is also an object to provide a novel means for actuating the coin chute or coin handling mechanism.

Another object is to utilize the coin itself through the force of gravity as much as possible in allowing the coin to reach a position where it will be determined to be authentic before it can positively be moved into the display Escalator.

Other important objects will become known as the disclosure is more fully made.

Generally the improved structure of the invention embodies a suitable frame carrying a shaft or the like to be released after operation of the coin handling mechanism by a proper coin. Such shaft will serve to operate a vendor or release

amusement apparatus for play, depending upon where the coin chute is used. The coin chute will be mounted on the frame in a generally upright position but tilted back out of the vertical.

- 5 A coin feed opening is provided and when a coin is inserted thereto it will drop or slide by gravity through a testing passage where means is present serving to by-pass magnetic slugs, or undersized slugs and coins, thus preventing such pieces from entering the operating position in the mechanism. Means is also associated with this entrance passage to prevent two coins from being simultaneously moved into the chute, such means being controlled to operate in a manner whereby 10 such two coins will be constrained to enter the operating position successively, thereby preventing jamming. With an authentic coin lodged and retained in said operating position at the receiving end of a display Escalator for moving the 15 coins to a cash box or the like, a manual means may be operated to positively move the coin into the Escalator and operate the vendor or other means depicted herein illustratively as a rock shaft. Said shaft has associated with it lock 20 means which is made ineffective by a proper coin held in the operating position mentioned. When a hand lever, or the like, is now operated to rock the shaft and operate the vendor or the like, means is simultaneously operative to engage and 25 press the coin downwardly from its operative position and move it into the display Escalator. This latter device comprises an endless slotted band arranged to enable coins to have an edge thereof fit into a respective aligned slot for moving 30 the coin, or a series of coins against an abutment step by step, behind a window for the reasons stated, and finally discharge the coins one at a time, in succession, from the coin chute or 35 handling mechanism. All parts of the mechanism are thereafter restored to initial position 40 ready to be operated upon the entrance of a succeeding proper coin into the mechanism, all as will subsequently be more fully described.

Reference is here made to applicant's copending application, Serial No. 226,615, filed August 2, 1938. The present application claims the coin handling mechanism as herein shown in one form, whereas the copending application claims a plural organization of the same mechanism 45 with a common selective operating means.

In the accompanying sheets of drawings illustrating a practicable example of the invention:

Figure 1 is a front elevational view, on substantially full size scale, of the improved coin handling unit per se;

Figure 2 is a rear view thereof;

Figure 3 is a side elevational view of the same unit mounted on a support or frame of a vendor cabinet, some of the manually operated coin moving means also being shown;

Figure 4 is a vertical section through the mechanism showing a coin held in the operating position;

Figure 5 is a front view of the Escalator mechanism viewed from the line 5—5 of Figure 3;

Figure 6 is a face detail view of a portion of the Escalator band;

Figure 7 is a detail front view, with a cover plate removed, of the magnetic slug by-pass means;

Figure 8 is a sectional view through one of the Escalator drive wheels taken along line 8—8 of Figure 5 looking in the indicated direction;

Figure 9 is a general side view of a typical coin operated machine cabinet carrying the improved coin handling mechanism and also showing the coin freed shaft and manual control lever, the parts being shown in starting or initial position;

Figure 10 is a view similar to Figure 9, but showing the parts in released position after the manual control lever has been swung forwardly;

Figure 11 is a reduced scale, front elevational view of the cabinet; showing the coin Escalator in dotted lines behind the window formed in the cabinet to display a number of previously handled coins; and,

Figure 12 is a front detail view of a part of the lever mechanism shown in Figure 4.

Looking at Figures 9, 10 and 11 it will be seen that the coin released machine, such as a vendor, may take any desired form, and comprises a cabinet 15, having a front wall 16, one upper portion of which is formed with an elongated vertical, glass covered, display opening, or window 17. Above, and to one side of the window is a circular opening in the wall 16 through which is projected the coin entrance sleeve 18 carried at the upper end of a front plate 19 disposed in an upright manner and tilted rearwardly as shown out of a vertical plane.

Inside the cabinet 15 is suitably positioned a frame comprising opposite, spaced side members 20, the front edges of which have secured thereto a rear plate 21 somewhat thicker than the front plate 19. These two plates 19 and 21 are substantially coextensive in size and shape and lie flatly one on the other, both being inclined from the vertical, as shown, and serving together as the mounting means or support for the coin chute mechanism of this invention. These two plates as a unit are secured to the front edges of the two spaced side frame members 20 by bolts 22 (Figure 3) which enter respective holes 23 provided in the plates 19 and 21 for that purpose.

At the lower portion of the cabinet 15 the frame 20 carries a cross rock shaft 24, one end thereof extending outwardly through an end wall of the frame where it carries fast thereon an upright operating member in the form of a hand lever 25. This shaft 24 when freed by the coin handling mechanism to be described, can be rocked by the lever 25 to operate any suitable means (not shown) as are common in the vendor and amusement machine art. One end of the shaft 24 inside the cabinet and adjacent one side member 20 carries fast thereon a lever 26 and an oppositely extending boss 27 also fast thereon. Thus the parts 26 and 27 rock with 75

the shaft 24. This end of the shaft 24 also carries loosely thereon a quadrant shaped member 28, one corner of which carries a transverse pin 29 engaging behind an edge of the arm 26, as shown. The quadrant 28 at another point carries a rigid, oppositely extending transverse pin 30 which normally is held in the narrowed end of an opening 31 formed in the proximate frame member 20, because of the pull of a spring 32 connected between the quadrant 28 and member 20 as shown in Figures 9 and 10. The quadrant between its pins is formed with a hump 33 normally engaged by a lock lever 34 pivoted intermediate its ends at 35 to the frame 20 and 10 biased by a spring 36 to engage one end of the lever 34 by said hump 33 as shown in Figure 9. A notch in the quadrant is formed at 33' adjacent the hump. A lifting link 37 has one end pivotally connected to the operative end of the 15 lever 34, as shown.

Adjacent the boss 27 the frame 20 by means of a pin 38 pivotally carries a lever 39 one end of which is engaged with the boss 27 while the other end has pivoted thereto, one end of an 25 upright link 40.

The link 37 is controlled by a proper coin held in operating position as will later appear, the coin causing the link 37 to be held raised whereby the latch 34, 33 is released to enable operation of the lever 25 and shaft 24. At the same 30 time the link 40 through boss 27 and lever 39 may be pulled down to operate mechanism to be described for positively moving a coin downwardly from its operating position into the Escalator, said Escalator also being driven as the 35 result of the upward movement of said link 40.

The link 40 has its upper end pivotally connected to a bell crank 41 (see Figure 4) pivoted on a pin 42 to member 20. The other corner of 40 the member 41 carries a rigid transverse pin 43 located in the notch 44 of the downturned end of a lever 45 pivotally connected by a shaft 46 to the frame 20. This lever 45 extends upwardly and forwardly and has a head end 47 shaped to 45 extend forwardly through a vertical, narrow, elongated slot 48 (see Figure 2) formed through the superimposed plates 19 and 21.

A latching lever 49 is also pivoted on the fulcrum 46 the same having a hooked free end 50 forming a notch 50 for a purpose later to be made known. The lever has a transverse extension 51 arranged over the back edge of the large lever 45 and a spring 52 connected between the extension 51 and lever 45 as shown in Figure 4 55 causes the lever 49 to move with lever 45 although the two are independently pivotally mounted on the fulcrum 46. The lever 45 is positively moved down as will appear and the spring 52 pulls latch lever 49 down with it, although the lever 45 makes a much longer down stroke since it is necessary for its head 47 to travel substantially the length of the slot 48.

The upper end of the link 37 as shown in Figures 3, 4 and 12 is pivotally connected by a transverse pin 53 fastened to a forwardly extending arm 54 integral with a sleeve 55 made fast to a cross shaft 56 journaled in the side members or end plates 20. The arm 54 is made wide so that it can rigidly carry two vertically spaced, transversely extending, parallel pins 57 and 58. The pin 57 extends into an opening 59 larger in diameter than the pin, and formed in an arm extension 60 extending forwardly from an upright lever 61 loosely pivoted intermediate its ends on the shaft 56. A spring 62 is connected between

an upper part of the lever 61 and the other pin 58 on arm 54. Relative movement, because of the loose connection 51, 59 can take place between link 37 and the loose lever 61. This lever 61 has a lower extension 62' and a rear extension 63, which extensions in this disclosure may be considered to serve as counterbalancing means for the lever 61. The upper end of the lever 61 is turned upwardly and forwardly and at its upper terminal end carries a transverse pin 64 for a purpose to appear.

There has now been described all of the auxiliary operating mechanism cooperating with the coin chute and released thereby for operation. The specific details of the coin handling mechanism will now be described.

The plate support 19 and 21 has an upper offset portion (see Figures 1 and 2) and a lower offset portion, the upper portion serving to carry the coin entrance passage and testing means, while the lower offset portion forms the display means cooperating with a coin Escalator.

Taking the upper offset portion first, as shown in Figure 1, it will be seen that the plates 19 and 21 between them are provided with a downwardly extending coin drop passage 65 leading from the coin drop opening 18. This passage at its lower end curves to the right as seen in Figure 1 and terminates in a position where the lower end of the slot 48 would approximately diametrically align across the face of a coin lodged at the lower end of said passage 65. In this latter position the coin, one of which is shown in dotted lines at 66 in Figure 1, is considered to be in the operating position where the coin machine parts may now be operated by the lever 25. (See also Figure 4.)

The two plates 19 and 21 are held flatwise together by screws 67. The front plate 19 is formed with a vertical slot 68 having a lower extension 69 extending across the offset portion of the coin passage 65. The upper part of slot 68 has a narrow upwardly extending extension 70. The rear plate 21 in back of the slot 68, 69 is formed with a similarly shaped slot 71 (Figure 2) of considerably greater width, in fact of a width designed to conform to the diameter of undersized coins such as pennies. The penny will be assumed herein to be undersize and the proper size coin will be considered the five cent piece. Thus, the back side of the coin drop passage 65 in advance of the operating position designated by coin 66 will be open and since the plates 19, 21 lean back, it follows undersized coins such as dimes and pennies will fall from the passage 65 through slot 71 before they can reach an operating position. Such rejected coins can be received by any suitable chute, not shown, and directed to any out of the way place in the cabinet, as may be desired.

On the front face of plate 19 on opposite sides of the slot 68 are ears 72 for mounting a cross shaft 73 on which is rockable intermediate its ends, a peculiarly shaped lever 74 having an upper hooked portion 75 passed back through the upper left hand part of slot 68 as shown in Figure 3. This upper portion is weighted as at 76 and 77 to provide proper balance against the lower end of the lever which is formed as an extension 78 movable in slot extension 69 and normally lightly held by the counterweights described in a position to be engaged by a coin or the like moving down the passage 65. This extension 78 cooperates with slot 71 to deflect undersize coins from the passage 65 in an obvious manner. Adjacent the upper end of the slot 68 above shaft

73 one edge of the slot is cut out to provide a projection 79 against the top edge of which the rear end of the hooked portion 75 abuts to limit the movement of the latter in an inward direction. The weights 76 and 77 being forward of the pivot 73 act normally to swing the tail 75 outwardly and hold the extension 78 inwardly so that a coin moving down the passage 65 must engage same.

The plates 19 and 21 below the coin entrance sleeve 18 and to one side thereof have a transverse slot 80 formed therethrough as appears in Figures 1 and 4, the front portion of the slot tapering downwardly as at 81. The back side of the plate 21, as seen in Figure 2, is provided with spaced ears 82 carrying a transverse shaft 83. Pivotedly hung from this shaft is a lever 84 shaped as the tail of an enlarged head portion 85 provided with counterweight means 86 to hold said lever normally back with its tail 84 extending forwardly into the slot 68 as shown in Figure 3. Secured to the head 85 of this lever is a laterally extending stop member 87, having a horizontal portion formed with a notch 88 and a front extension 89 curved downwardly to cooperate with and fit into the slot 80 already described. One edge of this head 85 proximate the entrance to the coin drop passage 65 will engage the edge of one coin when two coins are simultaneously fed into the spout 18 to make it possible for one coin only to enter the passage 65 and move therewith as will later more fully appear. A coin in the operating position, such as the coin 66 serves a cooperating locking function in this connection as will next appear.

Looking at the back side of the plate 21, as shown in Figures 2 and 4, it will be seen that on opposite sides of the upper end of the vertical slot 48 there are provided two spaced ears 90, carrying a cross shaft 91 on which is hinged, intermediate its ends, a generally upright lever 92. Said lever has a right angularly turned, upwardly extending portion 93 disposed in the notch 88 of the member 87. This lever extends quite a distance below its fulcrum and at its lower end is formed with a forwardly extending portion 94 and a rearwardly extending fork portion 95. The forward portion 94 extends through a vertical slot 96 formed in the plates 19 and 21 adjacent slot 48 so that the portion 94, as shown in Figure 4, may press against a coin held in the operating position in the passage 65, such as the coin 66 shown. The balanced weight of said lever 92 is such that the part 94 will tend to pass into the slot 96, unless a coin is in the operating position and then, of course, the part 94 will abut the back side of such coin. As shown in Figure 4, when a coin as 66 is abutted by the part 94, the lever 92 is locked against movement so that the upper part 93 thereof is pressed forwardly in the notch 88 to hold the stop member 89 forwardly in the slot 80 to prevent ingress of coins into the entrance to the passage 65.

The plate 21 along one edge is formed with a hook 96. Pivotedly carried on a pin 97 in a space 98 provided between the plates 19 and 21 is a latch member 99 which has a hook end 100. A spring 101 is connected between the hook 100 and hook 96 normally to pull the latch 99 so that the same may project its end into the slot 96 and abut the lower edge of a coin, such as coin 66, and positively hold same in the operating position at the lower end of the passage 65 as shown in Figure 1. As shown the movement of said latch 99 is limited by one edge of the space 98.

As shown in Figures 1 and 2 one edge of the

plates 19 and 21 is complementarily extended laterally to provide ears 102 between which is secured, by a screw 103, a horseshoe magnet 104, positioned horizontally, with the end of the lower leg rounded or curved as at 105. This magnet has its field disposed proximate a side edge of the coin drop passage 65 in a manner best to attract magnetic slugs dropping down the passage 65. (See Figure 7.) The ears 102 carry a small receptacle 106 therebelow and a slot 107 is formed in the rear plate 21 laterally from the passage 65 and directed toward the open top of the box 106 so that a magnetic slug will be magnetically attracted and drawn side or edgewise to the left, as viewed in Figure 7, and with the aid of gravity, caused to roll under and around the arcuate magnet leg 105 to pass through the slot 107 and into the box 106.

Going back now to lever 92, (Figure 4) the lower end thereof is forked as at 95, said fork spanning the pin 64 on the upper end of the lever 61. Play is permitted between the fork 95 and pin 64. The escalator for moving the coins out of the coin handling mechanism will next be described.

As shown in Figures 1, 2, 4 and 5 the back plate 21 at its lower offset portion below the operating position of the coin 66 carries by screws 107' in spaced relation to the plate 21, an auxiliary plate 108 of irregular shape. Below the operating position of the coin 66, the rear plate 21 is cut out to form a long vertical coin display passage 109 having an abutment edge 110. The top plate 19 has its lower offset portion extended slightly to overhang the abutment edge 110 so that coins moving down said display passage 109 are properly guided and cannot jump or be forced out. It will be understood that this display passage 109 is directly under or behind the window 17 (Figure 11) in the cabinet or housing 16, so that the coins in the passage 109 are readily visible at all times.

Upper and lower portions of the plate 109 carry an upper shaft 111 and a lower parallel shaft 112 (Figure 5). A front stationary plate 113 is carried on the shafts 111 and 112. Each shaft as shown in Figure 8 carries loosely, a novel form of reel mechanism for an endless escalator band, presently to be described. Each reel is numbered 114 and is built up of a series of laminated disks 115 secured together as a reel unit in any desired manner. A disk 115 of each reel is formed at angular intervals on its periphery with driver prongs 116 (Figure 8') and another disk in each reel has a smooth periphery to provide a spool surface for an endless steel band 117, which has spaced slots 118 to receive the lugs 116 whereby to drive the band. The band approximately on its center line is formed with large coin receiving slots 119 (see Figure 6), which individually receive coins in the manner indicated in dotted lines in Figure 8. The width of the slots 119, as well as their length may be varied in different bands in accordance with the size of the coins to be handled. The width or thickness of the inner disk 115 lying in the same plane with said slots 119 may similarly be altered by substitution to accommodate different thicknesses of coins. Said inner disk at angular intervals is formed with humps 120 (see Figure 5) thereby forming pockets 121 to receive coins sticking 70 through the band 117 and slots 119.

One end disk 115 is formed with notches to form ratchet teeth 122 at spaced intervals corresponding with the spacing of the driver lugs 116. Both reels 114 in the respects so far mentioned 75

are same. The plate 113 has an outstanding ear 123 carrying a pin or roller 124 serving to keep the band 117 properly guided and tensioned. A cross shaft 125 is carried by plates 108 and 113 5 intermediate the reels 114, said pin or shaft pivotally carrying a lever pawl 126 having at its ends respectively, oppositely faced pawl heads 127 as seen in Figure 5. These pawl heads engage in the notches or teeth 122 in the reels 114, as shown 10 in a manner to make these reels positively driven in the same direction. Rockable with the pawl lever 126 as an integral part thereof and also on axis 125 is an upstanding arm 128, the upper end of which carries a pin 129. To this pin is 15 connected a transverse pull spring 130 also connected to a pin 131 on the plate 108. The spring 130 always pulls on the lever 126 to hold the pawl heads 127 respectively, yieldingly against the notches or teeth 122 of the reels 114 in an obvious manner. As shown in Figure 2 the pin 129 extends rearwardly through a large hole 132 formed in the plate 108 to facilitate connection of the spring 130 to the post 131, which is on the back side of the plate 108.

Carried fast on the upper shaft 111 adjacent to but on the back side of the upper reel 114 is a toothed driver disk 133 positioned on the front side of the plate 108, said plate having a large arcuate slot 134 formed therein, as shown. The 20 shaft 111 on the back side of the plate 108 has fast thereon a lever 135 pivoted intermediate its ends. (See Figure 2.) This lever carries a pin 136 to which is connected a spring 137 in turn connected to a pin 138 mounted on the plate 108. This spring 137 normally acts to pull the right hand end of the lever 135 down as viewed from the rear. The upper right hand corner of this lever 135 carries a pivot pin 139 to which is pivoted a driver pawl 140 engageable with the teeth on disk 133, said pawl 140 having a hump 141 for a purpose to appear. A pin 142 on the pawl 140 has a pull spring 143 connected to it, the spring having its other end connected to a pin 144 on the lever 135. The spring 143 holds the pawl 140 in duty against the toothed disk 133. An upstanding part of the plate 108 carries a pin 145 against which the hump 141 engages to limit the stroke of the pawl 140 and lever 135.

The back side of the lever 135 at its upper left hand corner as viewed from the rear in Figure 2 carries a rearwardly extending pin 146. Pivotally connected to the pin 146 at its lower end is an upstanding link 147 the upper end of which is pivotally connected by means of a pin 148 to the lever 45. A pin 149 is carried by plates 108 and 113 opposite the pin 125, and pivoted intermediate its ends on said pin 149 is a lever 150 the lower end of which is pulled by a spring 151 connected to a spaced point on the plate 108. The upper end of the lever 150 is formed with a narrow goose neck extension 152 which rides always, under the pull of the spring 151, on a pin 153 mounted on the lever arm 135 below the point 146. As the point 146 of the lever 135 swings down about axis 111 the portion 152 rides over pin 153 so that the end of the portion 152 may be abutted by a tooth on the disk 133, thereby acting as a limit stop means to insure a proper amount of angular turning movement of the driver disk 133.

The lever 92 heretofore described, at its lower end carries a laterally extending pin 154 positioned in the path of movement of the lever 49 so that its hook portion or notch 50 may at times engage over and latch with the said pin 154.

This completes the description of the details of the improved coin handling and coin machine releasing mechanism. The operation thereof will now be summarized.

The purpose of the structure, of course, is to pass a proper coin through the handling mechanism to cause release of the sector member 28 so that the hand lever 25 may be swung to operate the coin controlled machine and at the same time cause linkage to be effective for moving coins from the coin passage 65 into the Escalator display means.

When a single authentic coin, let us say a five cent piece, is placed flatwise into the spout 18, it will enter the upper end of the coin passage 65, pass the head 87 which is held back by the balanced lever 84; also passing the portion 75 which is held forwardly by the weighted lever 74 and its tail 78 as it slides down the passage 65 and finally comes to rest in the operating position as indicated at 66 in Figure 1. Here the stop dog 99 serves to hold the coin. In this position the coin 66 swings back the tail portion 94 of the balanced lever 92 so that the upper end 93 of the latter moves forwardly in the notch 88 of the head 87, whereby to swing the latter forwardly. This results in placing the stop 89 into and through the slot 80, so that no coin for the time being can drop below the upper end of the passage 65 where it will be held by said projection 89.

With the lower end of the lever 92 thus pushed back by the coin 66, as seen in Figure 4, the edge of the fork 95 on the lower end of said lever 92 engages and pushes back on the pin 64 on the upper end of the lever 61 to rock the shaft 56 slightly clockwise as viewed in Figure 4. Thus, the front end of the arm 54 is raised so that its pin 53 will pull on and raise the link 37 an amount sufficiently to lift the right hand end of lever 34 as shown in Figure 9. The operator may now grasp the lever 25 and swing same forwardly to rock the coin machine shaft 24, since the latter is freed.

As the shaft 24 rocks counterclockwise as viewed in Figure 9 the arm 26 engages pin 29 and rocks the quadrant 28 to the left or forwardly against the pull of the spring 32. With the parts so released by a proper coin the stop end of lever 34 will clear and ride over the hump on the sector 28 just to the rear or right hand of the notch 33'. As the shaft 24 so rocks, the abutment 27 rocks in the same direction, whereby to push up on the front end of the lever 39, causing the link 40 to be pulled downwardly. As said link comes down the bell crank lever 41, as best seen in Figure 4, is swung to cause its pin 43 to move rearwardly in notch 44 of lever 45 to swing the forward end 47 thereof downwardly in the slot 48. At the same time the lever 49 also swings down by the pull of the spring 52, until the hook notch 58 thereof rides over the pin 154 to lock the lever 92 and with it, of course, the tail 94 which is engaging the coin 66 in its operating position. With the lever 92 temporarily latched it cannot at this instant swing, so the upper stop arrangement 93, 89 is still effective to prevent passage of coins down the passage 65. As the lever 45 continues its down stroke, its front nose end 47 engages the upper edge of the coin in the operating position and presses it downwardly with a force sufficient to retract the yieldable stop dog 99.

The coin 66 now passes below the dog which springs back into stop position to stop the next 75

coin entering the operating position. The first mentioned coin now enters the upper end of the display passage 109 where it engages in a slot 119 in the endless steel band 117.

5 As the lever 45 swung down it pushed down on the link 147, shown in Figure 2, to operate the lever 135 and pawl 140. Thus the ratchet disk 133 was turned one step and because of the reverse pawl lever 126 the two reels 114 are simultaneously turned one step in the same direction. This moves the run of the band 117 adjacent the abutment 110 downwardly, and with the coin carried therein, it follows the latter is moved one step down in display position behind the window 17 and held there until the band 117 is again moved. As shown in Figures 1 and 11 five coins are simultaneously held in display position by the Escalator band, the coins being fed in at the top as described, and eventually dropping out one at a time from the low end of the passage 109 into a cash box or any other desired place.

When the lever 25 is now released the spring 32 pulls the quadrant rearwardly until pin 30 engaging in the rear end of the slot 31 stops same, this position being shown in Figure 9. The parts now operate in the reverse order and assume their initial operating positions. That is the link 37 moves down; the link 40 moves up, the lever 45 is moved up, and likewise, the latch 49, thus freeing the lever 92 so that under its balanced weight the tail 94 is swung forwardly and the top part 93 thereof is swung rearwardly to free the stop member 89. The mechanism is obviously now ready for another coin to drop through passage 65 to the operating position as heretofore described. Next will be considered instances relating to attempts at operating the mechanism when fraudulent coins and slugs are used, or when it is attempted to swing the lever 25 when no coin or slug at all is used, or when the coin happens to be undersized.

If a magnetic slug is used it will be attracted and moved sidewise by the magnet 104, the slug with the aid of gravity rolling around the rounded leg 105 of the magnet and through the side slot 107 into the receptacle 106, as shown in Figure 7.

When no coin at all is used we have the mechanism set as in Figure 3 where no coin is held in the operating position, as at 65, and as a result the lever 92 by its weight is so balanced that the tail 94 extends forwardly through the slot 96. By means of pin 154 the lever arm 54 is rocked forwardly causing the link 37 to be held down. It follows, as shown in Figure 9, that before hand lever 25 can be rocked forwardly very far, that the tail on the end of the lever 34 will catch in the notch 33' and lock the sector 28 as well as the lever 25 against a full stroke. It follows, therefore, that the coin machine cannot be released if no coin is in the operating position holding the tail 94 of the lever 92 back.

Undersized coins, because the passage 65 leans back from the vertical, hit the tail extension 78 and are deflected thereby flatwise rearwardly out through the enlarged slot 11 as has been explained.

When a coin is in the operating position, as at 66, another coin cannot be passed down the passage 65, because the first coin 66 holds the tail 94 of lever 92 back and the portion 93 thereof forwardly to press the stop head 89 into a position to obstruct the upper end of the

passage 65 and prevent the second coin from passing down the passage 65 against the previous coin held in the operating position. This safe-guard prevents the possibility of successive coins jamming in the passage 65.

If unauthentic coins or slugs should pass the above safe-guards provided, and enter the operating position to enable release of the coin machine, it is but an instant before such coin will be lodged in the display position passage 109, 10 where for five operations the improper coin will be displayed to shame the player.

It can now be seen that an improved mechanism has been provided for the purposes stated, which achieves the objects heretofore recited.

The intention is to cover all changes and modifications of the example herein chosen for illustrative purposes, which do not in fact constitute departures from the spirit and scope of the invention as expressed in the appended claims.

What is claimed is:

1. For a coin operated machine having a manually moved means adapted for operation when a proper coin is used and coin handling means comprising a support formed with a coin passage inclined from the vertical but permitting a coin entering same to pass edgewise therealong by gravity to an operating position, said position provided by a lateral curvature in the passage, means at said position releasably to hold a coin, means operatively associated with the coin handling means releasably to lock the manually moved means against operation, means comprising a movable member carried by the support and engageable by a coin in the operating position to release the lock means, means operable by the manual means to move the coin from said operating position to discharge same into one end of a straight display passage provided on the support below the operating position; a movable Escalator comprising an endless reel and web mechanism carried by the support and provided with means to receive and hold coins discharged from the operating position, and means operable by the means that moves a coin from the operating position to cause the Escalator mechanism to move the coins along the display passage step by step and discharge same successively from the other end thereof.

2. For a coin operated machine having a rock shaft to be moved by a hand lever and means releasably to lock the shaft against movement comprising a coin handling mechanism, said mechanism having a frame formed with an upright coin testing passage along which a coin may slide by gravity to an operating position at the lower end of the passage, said position provided by a lateral curvature in the passage, means operable when a coin is passed through said passage to the operating position to unlock the rock shaft

for movement, means operable upon movement of the rock shaft to engage and push a coin down from the operating position into a coin display passage provided in the frame at its lower end;

5 an endless band having means to receive coins discharged from operating position, said band forming one side of the display passage and mounted on the frame, means to drive the band to move coins through the display passage, and means for driving the latter means from the means that pushes the coins from the operating position.

3. A coin handling mechanism having a frame provided with a coin testing passage disposed vertically to receive coins edgewise so that they gravitate to the lower end of the passage to an operating position, said position provided by a lateral curvature in the passage, means releasably to hold a coin in the said position, a coin

15 machine mechanism, means operable when a coin is in said position to release the coin machine mechanism for operation, means operable to move a coin from operating position down into a display passage arranged vertically in the frame below the operating position to receive coins edgewise discharging from the operating position, said 20 two passages being substantially parallel but offset from one another by means of a curved lateral extension at the lower end of the testing passage, and means operable when the coins are moved into the display passage to receive and move the coins through the latter passage.

4. In a coin handling mechanism, a frame having a passage with an abutment edge along which 25 30 coins are movable edgewise, an endless reel and web means carried by the frame with the web having slots at intervals therein to receive coins and move same along the abutment edge, each reel comprising a superposed pack of disks secured together, one disk in each reel having spaced peripheral driver prongs engaging in spaced slots formed in the web, another disk in each reel having angularly spaced peripheral pockets to receive coins projected through the 35 coin slots in the web, and another disk having peripheral teeth to be engaged by a driver pawl included in the mechanism for driving the reels.

5. Coin Escalator means comprising a support, 40 a pair of spaced reels turnably carried thereon, a flexible metal band trained around the reels and having between its edges slots chordally to hold and receive coins edgewise, said reels each constructed of a pack of disks held removably together, with at least one disk in each pack and reel having driver prongs on its periphery to engage in complementary slots formed in the band, and at least one other disk in each pack and reel having coin receiving pockets formed in its periphery.
